(57) **CLAIM**

(21) Appl. No.: **29/166,305**

We claim the ornamental design for a waterproof tackle box
having mako shark indicia, removable flash light in side
recess, and built-in AM/FM radio, as shown and described.

(22) Filed: **Aug. 26, 2002**

DESCRIPTION

(51) LOC (7) Cl. **03-01**
(52) U.S. Cl. **D3/260**
(58) Field of Search D3/260, 904, 905,
D3/294, 273, 259; D22/134, 136; 43/54.1,
55, 57.1, 25.2, 26; 206/315.11

FIG. 1 is a perspective view of the waterproof tackle box
having mako shark indicia, removable flash light in side
recess, and built-in AM/FM radio, embodying the design of
the present invention;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof; and,

FIG. 7 is a bottom plan view being identical thereto.
